UNITED STATES PATENT OFFICE

2,419,801

BATHTUB CONSTRUCTION

Frank P. Uphues, Chicago, Ill., assignor to Crane
Co., Chicago, Ill., a corporation of Illinois

Application May 15, 1944, Serial No. 535,703

3 Claims. (Cl. 4—173)

1

This invention relates to bath tubs and the like and is more particularly concerned with a bath tub construction in which an ornamental prefabricated enclosure unit is provided for preliminary installation in a bathroom and is formed with an opening therein to receive a bath tub for demountable support and connection therewith.

In the construction of bathrooms it has heretofore been the practice to provide bath tubs with an integral enclosing and supporting skirt extending from the upper end of the bath tub to the floor on the exposed portion thereof, and with integral flange portions extending from the bath tub for substantially permanent engagement with the adjacent wall structure. This form of construction is commonly known and is referred to as the built-in type of bath tub. It is desirable due to its compact appearance and space saving arrangement, but it embodies certain objectionable features which the applicant's invention has been designed to overcome. It has heretofore been the practice necessarily to install the built-in type of tub during the early part of the construction of a house and to thereby subject the tub to severe abuse and damage during final construction. In the event this type of tub is so damaged as to necessitate its removal during construction or thereafter, the expense and labor is relatively very great due to its built-in features as referred to. Another disadvantage inherent in this type of tub resides in the frequent formation of cracks between the tub and its line of connection with the walls of a room due to shrinkage or shifting of the tub. These and other disadvantages have been overcome in applicant's improved tub construction as hereinafter set forth.

Briefly, this invention comprises a tub enclosure having a top portion formed with an opening therein to receive a tub for demountable engagement therein. Flanges extend upwardly from the top portion of the enclosure for engagement with the walls of a room, and a skirt extends downwardly from other sides of the top portion and from wall to wall to conceal that portion of the tub remote from the wall. Longitudinally and transversely disposed frame supports are provided for fixed, built-in engagement with the room structure to engage and support the underside of the tub and its enclosure member. A suitable sealing engagement is provided between the periphery of the opening in the enclosure and the tub to prevent leakage therebetween.

An object of this invention is to provide a bath

2

tube construction in which a suitable tub enclosure may be built into a bathroom and provided with an opening to receive a bath tub for leak-proof, detachable engagement therein to permit the ready installation or removal of the bath tub during construction or thereafter, thereby retaining the advantages of a built-in bath tub construction and also permitting the relatively easily marred tub to be readily installed or removed after construction of the bathroom.

Another object of this invention resides in the provision of a bath tub construction in which the bath tub enclosure and the bath tub may be formed of dissimilar materials, and the enclosure may be of various sizes and shapes to suit the selected bathroom dimensions while the bath tub or basin portion may be formed in a single size or shape if desired.

A further object of this invention resides in the provision of a bath tub construction in which a shrinkage or shifting of the bath tub does not cause the formation of cracks or other damage on the walls of a bathroom.

This invention further contemplates in combination therewith the provision of novel supporting means for a bath tub and its enclosure whereby their combined weight is distributed over a relatively large supporting area by forming a base for the same consisting essentially of longitudinally and transversely extending supporting members.

The invention embodies other novel features, details of construction and arrangement of parts which are hereinafter set forth in the specifications and claims and illustrated in the accompanying drawings, forming part thereof, wherein:

Fig. 1 is a perspective view showing a bath tub construction for enclosure by three walls of a room and embodying features of this invention.

Fig. 2 is a longitudinal sectional view taken along the line 2—2 of Fig. 1.

Fig. 3 is a transverse sectional view taken along the line 3—3 of Fig. 1.

Fig. 4 is a perspective view showing a modified form of bath tub construction for built-in engagement with two walls of a room.

Fig. 5 is a transverse sectional view showing a further modification of this invention in which the supporting flange provided on the tub enclosure is turned upwardly for engagement under a rolled-over rim flange formed on the tub.

Referring now to the drawings for a better understanding of this invention, a bath tub 6 is formed with a bottom 7, walls 8, and a flange 9

which extends outwardly from the upper periphery of the walls 8. A tub enclosure 10 is formed with a top portion or surface 11 which is bent inwardly at 12 and then parallel with the top portion to provide a supporting flange 13 defining an opening 14 to receive the tub. A skirt 16 is bent downwardly from the top surface to conceal the lower portion of the tub, and side flanges 17 are bent upwardly from the top surface for line engagement with the wall surfacing material (not shown). The lower end of the skirt may be bent inwardly at 18, if desired, to provide toe space.

Longitudinally extending supporting members 19 and transversely extending members 21 are disposed under the bath tub and the enclosure 10 to support same and preferably having their upper edges conforming to the outline of the surfaces being engaged thereby. The end portions 22 of the members 19 and 21 are provided for engagement with the structural members of a house, and the bottom edges 23 of the members cover a relatively large area to distribute the load thereon.

A sealing gasket 24 formed of any suitable material is preferably interposed between the supporting flange 13 and the bath tub flange 9, and a sealing material 26 is mounted in the corner defined by the enclosure portion 12 and the flange 9. The bath tub may be gripped and lifted from its position in the enclosure member by means of the usual drain opening 27 and overflow opening 28 formed therein.

Fig. 4 shows a modified form of this invention in which the skirt 16 extends along one side and one end of the enclosure 10, the invention being thus applied to the corner type of tub. Several of the transversely extending supporting members 21 in this view are shown in incomplete outline in order to avoid possible confusion from intersecting dotted lines.

Fig. 5 shows a further modification of this invention in which an enclosure member 31 is provided with an upturned supporting flange 32 for engagement under a rolled-over flange 33 formed on the bath tub 34.

While this invention has been shown in several forms it is obvious to those skilled in the art that it is not so limited but is susceptible of various changes and modifications without departing from the spirit thereof or the appended claims.

I claim:

1. The combination with a bath tub having a rolled-over rim portion, of an enclosure member having a top portion to receive a bath tub, a vertically disposed tub supporting flange defining an opening in said top portion, a skirt portion ex-

tending downwardly from said top portion, and flanged portions extending upwardly from said top portion and along the side thereof not provided with the skirt portion, floor supported members disposed beneath the said bathtub having their upper edges conforming to the outline of a portion of the exterior surfaces of the bathtub.

2. The combination with a bath tub having a rolled-over rim portion, of an enclosure member having a top portion to receive a bath tub, a vertically disposed tub supporting flange defining an opening in said top portion, a skirt portion extending downwardly from said top portion, flanged portions extending upwardly from said top portion and along the sides thereof not provided with the skirt portion, and longitudinally and transversely extending supporting members engaging the undersides of the bath tub and said top portion, the said supporting members having upper portions for support of the flanged portions of the said enclosure member extending upwardly from said top portion.

3. A combined bathtub and enclosure member therefor, the said enclosure member having a top portion to receive the bathtub, a vertically disposed bathtub supporting flange defining an opening in the said top portion, a skirt portion extending downwardly from said top portion, flanged portions extending upwardly from said top portion and along the sides thereof not provided with the skirt portion, a frame underlying the enclosure and portions of the bathtub, the said frame comprising cross-connected supporting means with end projecting portions for engagement with a room element, said means supporting the underside and walls of the bathtub and the enclosure.

FRANK P. UPHUES.
